CLAIM

The ornamental design for a pen with a box set, as shown and described.

DESCRIPTION

FIG. 1 is a perspective view of the pen with a box set showing my new design, where in the pen is inserted into the box;

FIG. 2 is a detail, perspective view of the upper portion of the pen with a box set, where in the pen is inserted into the box;

FIG. 3 is a perspective view of the box portion isolated from the pen, for ease of understanding;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is a perspective view of the pen portion isolated from the box, for ease of understanding;

FIG. 11 is a detail, perspective view of the upper portion of the pen isolated from the box;

FIG. 12 is a front elevational view thereof;

FIG. 13 is a rear elevational view thereof;

FIG. 14 is a left side elevational view thereof;

FIG. 15 is a right side elevational view thereof;

FIG. 16 is a top plan view thereof; and,

FIG. 17 is a bottom plan view thereof.

The broken lines represent the bounds of the detail view and form no part of the claim.

1 Claim, 9 Drawing Sheets
